Primary Examiner — Maria J. Edwards*Assistant Examiner* — Dina Michelle Hoeynck(74) *Attorney, Agent, or Firm* — WHDA, LLP(57) **CLAIM**

The ornamental design for a lens for infrared radiation sensor, as shown and described.

DESCRIPTION

FIG. 1 is a perspective view of a lens for infrared radiation sensor showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a cross-sectional view thereof taken along lines 8-8 of FIG. 3.

The oblique line shading in the drawings represents transparent or translucent surfaces. Showing of internal construction is omitted from the cross-sectional view.

1 Claim, 8 Drawing Sheets(56)
